(57) **CLAIM**

The ornamental design for a roller support frame, as shown and described.

DESCRIPTION

FIG. 1 is a top, side perspective view of the roller support frame showing our new design;

FIG. 2 is a side elevation view thereof;

FIG. 3 is an opposite side view thereof;

FIG. 4 is a top view thereof;

FIG. 5 is a bottom view thereof;

FIG. 6 is a first end elevation view thereof; and,

FIG. 7 is an opposite end elevation view thereof.

The broken lines in the drawings depict portions of the roller support frame that form no part of the claimed design.
